SOUTH AFRICA.

ELECTROLYTIC CELL.

1,334,419.

Specification of Letters Patent. Patented Mar. 23, 1920.

Application filed November 5, 1918. Serial No. 261,172.

To all whom it may concern:

Be it known that I, URLYN C. TAINTON, a subject of the King of Great Britain, residing at Doornfontein, Johannesburg, 5 Transvaal, United South Africa, have invented new and useful Improvements in Electrolytic Cells, of which the following is a specification.

This invention relates to an electrolytic 10 cell, and one of the objects of the invention is the treatment of relatively large quantities of solution in a very rapid and thorough manner. The cell is especially applicable to the precipitation of gold and silver from 15 cyanid solutions, and may also be employed for selective precipitation of metals, and for other purposes, for instance, the separation of cadmium and copper from zinc solutions by the application of a preferential 20 voltage, or for the oxidation of manganate to permanganate, and the like.

Another object of the invention is to provide a cell comprising a casing in which is mounted a plurality of fixed electrodes, and 25 a plurality of intermediate revolving electrodes, between which the solution to be treated is passed, and furthermore to provide a porous inclosure for each fixed electrode to permit the formation of a solution 30 chamber about each electrode, and also to prevent the circulating solution to be treated from mixing with the solution about the fixed electrodes and from contacting with the fixed electrodes. This feature is of con- 35 siderable importance, for instance, in the precipitation of gold from a cyanid solution the rotating electrodes are made cathodes and the fixed electrodes anodes. The separation of the anodes with relation 40 to the cathodes produces several important advantages, firstly, by preventing the contact of the current electrolyte with the anode the usual anodic destruction of cyanid is avoided, thus the whole of the cyanid 45 regenerated by the deposition of metal at the cathode is rendered available; secondly, the inclosing of the anode permits the concentration of negative ions in the anode chamber under the influence of the potential gradient. The solution in the anode 50 chambers thus quickly becomes acid in which a lead anode is far more permanent than in alkaline solution.

Another object of the invention is to pro- 55 vide an electrolytic cell in which the cas-

ing is preferably cylindrical and built up from a number of annular sections, there being as many sections as there are fixed and rotary electrodes, said sections being bolted together by draw bolts in such a manner that the casing may be easily assembled or taken apart to render the electrodes accessible for inspection or repair. 60

Further objects will hereinafter appear.

The invention consists of the parts and 65 the construction and combination of parts as hereinafter more fully described and claimed, having reference to the accompanying drawings in which—

Figure 1 is a view in side elevation of the 70 electrolytic cell partly in section.

Fig. 2 is a cross section on line 2—2 of Fig. 1.

Fig. 3 is a cross section on line 3—3 of Fig. 1. 75

Fig. 4 is an end view of Fig. 1.

Referring to the drawings in detail, A indicates in general a cylindrical shaped casing, which, in this instance, is built up of a plurality of annular sections such as shown 80 at 2 and 3. Positioned at each end of the casing is a head member such as shown at 4, and formed on the outer periphery of the head members are a plurality of perforated projecting lugs 5, through which are passed 85 draw bolts 6 by which the heads and the intermediate annular sections 2 and 3 are secured together. The sections 2 and 3 may be constructed of any suitable insulating material such as wood, cement, vulcanite, 90 or the like, while the head sections 4 to which the pressure is applied may be constructed of cast iron, insulating plates 7 being, however, interposed between each head and the annular segments as shown. 95 Suitably secured within each annular section 2 is an electrode 8. These electrodes are preferably circular in shape, and are spaced with relation to the inner surface of the sections 2 by means of blocks or wedges 9, 100 each electrode being otherwise secured by a contact post 10 which passes through the sections 2 as shown to permit the electrical connections to be readily attached. Formed in each electrode 8, is a central opening 11, 105 and surrounding each fixed electrode is a fabric covering 12, preferably constructed of canvas. This covering is constructed of two circular sheets of canvas which are sewed or otherwise secured together in the 110

central opening 11, while the outer edge or periphery of each canvas disk is secured by passing the same between the annular sections 2 and 3, they being here positively secured when the sections are drawn together by means of the bolts 6.

Formed in each head member 4 is a bearing 13, which is provided with a suitable form of stuffing box as shown at 14, and 10 extending through the box and the bearings shown, is a shaft 15, upon which is secured a plurality of electrodes 16. These electrodes are interposed between the fixed electrodes 8. They are circular in shape and 15 may or may not be perforated as conditions may require. Each electrode 16 is secured to the shaft by flange collars as shown at 17, and will, therefore, rotate with the shaft when power is transmitted thereto by a 20 pulley 18' or by any other suitable means.

The solution to be treated is admitted through a pipe 18, and will thus pass lengthwise through the casing between the several electrodes before it can escape through the 25 discharge pipe shown at 19. The casing as a whole comprising the sections 2 and 3 and the heads 4 are supported by a channel iron frame consisting of two end sections 20 and 21 and a pair of interspaced supporting 30 channel rails 22 and 23, lugs 24 being formed both on the heads and on the sections 2 and 3 to permit the casing to be readily supported. Any other suitable support may, however, be provided, but the present supporting 35 frame shown is probably preferable, as it permits the heads and the intermediate sections 2 and 3 to be separated and moved upon the supporting rails 22 and 23 when assembled or separated, thus rendering it 40 comparatively easy to handle each section and to obtain a perfect alinement of the perforated lugs 5 when they are moved into position.

The electric current employed, for instance, if a cyanid solution containing gold and silver is to be treated is passed through the cell in such a manner that the fixed electrodes become anodes and the revolving electrodes cathodes, the connections with the 45 circuit being established by passing one side of the circuit through the shaft by means of a brush and a contact ring, while the other side of the circuit is connected with the binding posts 10 of the fixed electrodes as shown.

50 In actual operation the solution to be treated enters through the pipe 18, and then passes endwise through the casing from one end to the other, and on its way is, therefore, subjected to the electrolytic action of the revolving electrodes. The solution does not come in contact with the fixed electrodes, and it therefore undergoes only one kind of treatment, either cathodic or anodic, as the 55 case may be. If the cell is used, for instance, in the oxidation of manganate to permanga-

55 nate, the rotating disks are made anodes, and the cathodes are inclosed in the canvas diaphragm whereby the reducing action of the cathode is avoided. In the precipitation of gold or silver from cyanid solution, 70 the rotating disks are made cathodes and the anodes are inclosed. This gives a double advantage; first, by preventing the contact of the current solution with the anode the usual anodic destruction of cyanid is avoided. 75 The whole of the cyanid regenerated by the deposition of metal at the cathode is thus rendered available. Secondly, the inclosing of the anode permits the formation of a solution chamber about each anode, thus establishing 80 concentration of negative ions in the anode chambers under the influence of the potential gradient. The solution in the anode chambers thus quickly becomes acid in which a lead anode is far more permanent 85 than in an alkaline solution.

90 In order to permit the escape of gas generated in the inclosed compartment of the cell, openings are provided at the top of each annular section. Valves 40 preferably of the float type are here inserted, thus permitting the escape of gas, but not of solution. Again, ordinary valves may be employed, and, in this case, are opened just enough to permit the escape of gas. During the 95 operation of the electrolytic cell it can readily be seen that metal, for instance, gold or silver, carried in the solution to be treated is deposited on the rotating electrodes. It may here be allowed to grow 100 into solid form, or by using a suitably high current density may be deposited in a loose non-adherent form which is detached by the friction of the solution, the precipitated metal thus passes out in suspension, and may 105 be readily separated by filtration or settlement.

An electrolytic cell constructed as here shown has proven of great value for several reasons: First, because with a comparatively 110 small apparatus it is possible to quickly handle a great quantity of solution, this being due to the fact that the flow of the solution is an additive quantity to the ionic migration in which the time required to effect 115 a clean separation of the metallic constituents of the electrolyte from the containing solution is greatly facilitated by bringing the ions into intimate contact with the revolving electrodes. The energy necessary 120 for precipitation of the metal and the capacity of the cell are, in consequence, reduced to a considerable degree; second, the whole of the cyanid regenerated by the deposition of metal at the cathode is rendered 125 available; third, destruction of cyanid is practically avoided, as the circulating solution does not contact with the anodes, thus preventing anodic destruction of the cyanid; fourth, acidity of the solution in the imme- 130

diate vicinity of the anodes is quickly established, and is permanently maintained, thus rendering the lead anodes far more permanent than when subjected to an alkaline solution; fifth, construction of the casing is such that all parts can readily be insulated one with relation to the other, and all parts may furthermore be readily assembled or taken apart as the operator may desire.

10. While a specific form of structure is here shown, I wish it understood that the materials and finish of the several parts employed may be such as the experience and judgment of the manufacturer may dictate.

15. I also wish it understood that various changes in form, proportion and minor details of construction may be resorted to within the scope of the appended claims, and that I do not wish to limit myself to the specific 20 design and construction here shown.

Having thus described my invention, what I claim and desire to secure by Letters Patent is:

1. In an electrolytic cell, a set of fixed and 25 movable electrodes, means for passing an electrolyte between the electrodes, and means for substantially preventing the electrolyte from contacting with one set of electrodes.

2. In an electrolytic cell, a housing for 30 the reception and passage of an electrolyte, a set of fixed electrodes within the housing, a set of movable electrodes within the housing, and means for substantially maintaining the electrolyte out of contact with one 35 set of electrodes during its passage through the housing.

3. In an electrolytic cell, a plurality of fixed and a plurality of movable electrodes, and a porous housing inclosing one set of 40 electrodes.

4. In an electrolytic cell, a plurality of fixed electrodes, and a plurality of movable electrodes, and a porous housing inclosing each fixed electrode.

45. 5. In an electrolytic cell, a plurality of fixed electrodes and a plurality of rotary electrodes, and a fabric covering inclosing each fixed electrode and space therefrom.

6. In an electrolytic cell, a housing for 50 the reception and circulation of an electrolyte, a set of fixed electrodes within the housing, a set of rotary electrodes, and means for substantially preventing the electrolyte from contacting with the fixed electrodes 55 during its passage through the housing.

7. In an electrolytic cell, a housing for the reception and circulation of an electrolyte, a set of fixed electrodes within the housing, a set of rotary electrodes, and a 60 porous covering spaced with relation to each fixed electrode and inclosing the same to substantially prevent the electrolyte during its passage through the casing from contacting with the fixed electrodes.

65. 8. In an electrolytic cell, a plurality of

circular electrodes having a rotary movement in a plane transverse to the flow of the electrolyte, a plurality of fixed electrodes interposed between the rotating electrodes, and means for substantially preventing the electrolyte during its passage between the electrodes from contacting with the fixed electrodes.

9. In an electrolytic cell, a plurality of circular electrodes having a rotary movement in a plane transverse to the flow of the electrolyte, a plurality of fixed electrodes interposed between the rotating electrodes, and a porous housing inclosing each fixed electrode and spaced therefrom to 70 form a solution chamber about each fixed electrode, and to substantially prevent the circulating electrolyte from mixing with said solution and from contacting with the fixed electrodes.

10. An electrolytic cell comprising a casing consisting of a plurality of ring sections secured together, a fixed electrode secured interior of each alternate ring section, said fixed electrodes each having a 75 central opening formed therein, a head member at each end of the casing, a shaft extending through the casing and journaled in the head members, means insulating the shaft from the head members and the casing, a plurality of electrodes secured on the shaft intermediate the fixed electrodes, means for imparting a rotary movement to the shaft and the electrodes carried thereby, means for passing an electrolyte from end 80 to end through the casing, and means for substantially preventing the electrolyte during its passage through the casing and between the electrodes from contacting with the fixed electrodes.

11. An electrolytic cell comprising a casing consisting of a plurality of ring sections secured together, a fixed electrode secured interior of each alternate ring section, said fixed electrodes each having a 85 central opening formed therein, a head member at each end of the casing, a shaft extending through the casing and journaled in the head members, means insulating the shaft from the head member and the casing, 90 a plurality of electrodes secured on the shaft intermediate the fixed electrodes, means for imparting a rotary movement to the shaft and the electrodes carried thereby, means for passing an electrolyte from end to end 95 through the casing, and a fabric covering inclosing each fixed electrode and spaced therefrom to form a chamber about each fixed electrode for the reception of an electrolyte and to substantially prevent the circulating electrolyte from mixing with the electrolyte about the fixed electrodes, and from contacting with the fixed electrodes.

12. In an electrolytic cell, a housing for the reception and circulation of an electro- 100

lyte, a set of fixed electrodes within the housing, a set of rotary electrodes entirely submerged in the electrolyte passing through the housing, and means for substantially preventing the electrolyte from contacting with the fixed electrodes during its passage through the housing.

13. In an electrolytic cell, a plurality of movable electrodes, a plurality of fixed electrodes interposed between the movable electrodes, means for maintaining a body of electrolyte about one set of electrodes, and means for passing a second body of electrolyte through the cell and substantially out of contact with the first named body of electrolyte.

14. An electrolytic cell comprising a housing, means for circulating an electrolyte

therethrough, a plurality of movable electrodes within the housing, a plurality of **20** fixed electrodes interposed between the movable electrodes and a porous housing inclosing each fixed electrode and spaced therefrom to form a solution chamber about each fixed electrode, and to substantially prevent **25** the circulating electrolyte from mixing with said solution and from contacting with the fixed electrodes.

In testimony whereof I have hereunto set my hand in the presence of two subscribing **30** witnesses.
